UNITED STATES PATENT OFFICE.

WILLIAM L. DENIO, OF ROCHESTER, NEW YORK, ASSIGNOR OF ONE-HALF TO HAROLD H. SIMMS, OF ROCHESTER, NEW YORK.

RECORD-CLEANER.

1,296,779.

Specification of Letters Patent. Patented Mar. 11, 1919.

Application filed May 23, 1918. Serial No. 236,229.

To all whom it may concern:

Be it known that I, WILLIAM L. DENIO, a citizen of the United States, and resident of Rochester, in the county of Monroe and 5 State of New York, have invented certain new and useful Improvements in Record-Cleaners, of which the following is a specification.

The present invention relates to record 10 cleaners for talking machines and more particularly to the type which operates in advance of the stylus or needle, for the purpose of cleaning the surface of the record during the rotation of the latter, an object of this 15 invention being to provide a construction which is simple in form and inexpensive to manufacture, and does not require any special devices for mounting it in place. A still further object of the invention is to 20 provide a cleaner which will utilize the centering pin of the record as an anchor by which the cleaner will be held to clear the face of the record under the influence of the reproducer as the table and the record turn.

25 To these and other ends the invention consists of certain parts and combinations of parts all of which will be hereinafter described, the novel features being pointed out in the appended claims.

30 In the drawings:—

Figure 1 is a plan view of portions of a talking machine equipped with the present invention;

Fig. 2 is a perspective view of the under 35 side of the cleaner;

Fig. 3 is an edge view; and

Fig. 4 is a plan view of a modification.

Referring more particularly to the drawings, 1 indicates a record supported on a 40 centering pin 2 which projects from a rotary table 3. With the record, the stylus or needle 4 of the reproducer 5 coöperates, the latter being supported in any suitable manner. The foregoing parts are all now generally used in talking machines.

The improvement embodies a member 6 which may be in the form of an elongated strip of thin sheet material, such as thin cardboard, celluloid, or the like. This strip 50 is provided at one end with one or more openings 7 situated at different distances from the end of the strip. These openings are adapted to receive the centering pin 2

of the record support so that the strip may be held by the centering pin as the table 55 turns to carry the record beneath the strip. The openings 7 are provided in order that the strip may be adapted to records of different diameters. Instead of a plurality of openings, slot 7a may be provided, as shown 60 in Fig. 4. To the under side of the strip, a strip 8 of outing flannel or other brush material, preferably a textile material with a pile or nap, is secured preferably by an adhesive. 65

When the device is in position on the centering pin, the brush material rests on the record which, upon turning, swings the cleaner so that an edge of the latter abuts the stylus on the side of the record in advance of the stylus, thus clearing the record of dust. Further turning of the record maintains the cleaner against the stylus. The device is very simple in construction and inexpensive to manufacture. The uppermost 75 face may have an advertisement thereon and in this way an advertising novelty is provided.

What I claim as my invention and desire to secure by Letters Patent is:

1. A talking machine comprising a rotary table with a record centering pin, a record on the table, and a reproducer coöperating with the record; combined with a cleaner held by the centering pin arranged to engage the reproducer to operate over the face of the record as the latter turns with the table.

2. A cleaner for records of talking machines comprising an elongated flat strip 90 having an opening at one end for the record centering pin and a brush surface on its under face for coöperating with the grooved face of the record when the latter turns with the table.

3. A cleaner for records of talking machines comprising an elongated strip of sheet material having near one end a plurality of openings at different distances from the end to fit on the centering pin of a record supporting table, and a strip of textile material, with a pile or nap, secured to the elongated strip to coöperate with the grooved face of the record as the latter turns with the table.

W. L. DENIO.
